Inventor
Frank P. McCord,

By *Clarence O'Brien*
Attorney

UNITED STATES PATENT OFFICE.

FRANK P. McCORD, OF MEXICO, MISSOURI.

ARCH SUPPORTER.

Application filed January 25, 1927. Serial No. 163,401.

The present invention relates to an arch supporter and has for its prime object to provide a structure which may be incorporated in a shoe for supporting the arch and the metatarsal regions of the foot in an efficient and reliable manner.

A still further very important object of the invention lies in the provision of a device of this nature which is simple in its construction, comparatively inexpensive to manufacture, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

20 In the drawing:—

Figure 1 is a side elevation of the arch support embodying the features of my invention showing the manner in which the same is positioned in a shoe,

25 Fig. 2 is a top plan view of the support,

Fig. 3 is a transverse section therethrough taken substantially on the line 3—3 of Fig. 2.

Referring to the drawing in detail it will be seen that the numeral 5 denotes an elongated strip of flexible material preferably leather under which is secured an elongated strip of metallic material 6 of a resilient nature by means of rivets 7 and 8. The flexible strip 5 extends beyond the forward end 35 of the strip 6 and is cut away at its upper surface to form a metatarsal supporting hump 9 which includes a V-shaped edge 10 and an arcuate forward edge 11. The median longitudinal dimension of the hump 9 is angularly disposed to the median longitudinal dimension of the strip 6. The forward edge of the strip 6 has a V-shaped notch 12 to receive the apex of the hump 9. The strip 6 is bent longitudinally in an 45 ogee manner to form the forward upward bowed portion 13 and a downwardly rear bowed portion 14. It will thus be noted that the apex of the hump points towards the inner portion of the foot, conforming to the 50 angle of the foot and making the support

for the foot in the metatarsal region and throwing the foot in natural position. Wings 15 extend laterally from the longitudinal edges and are formed integrally with the strip 5 being much thinner than said strip 5 as is clearly seen in Fig. 3 of the drawing.

The support is mounted in the shoe as is illustrated to advantage in Fig. 1, that is, the rear portion thereof is disposed in the heel and extends from the heel forwardly over the arch of the shoe to terminate below the metatarsal regions of the foot. This arch support is to be placed between the inner and outer soles of the shoe in the region of the instep, making a filler for the shoe, and the wings extend outwardly on either side and are sewed between the inner and outer soles for anchoring the arch.

It is thought that the construction, utility, and advantages of this invention will now be apparent to those skilled in this art without a more detailed description thereof. The present embodiment of the invention has been disclosed in detail by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:—

An arch support of the class described comprising a flexible leather sheet and a superimposed resilient metallic strip secured thereto, the leather sheet extending beyond the forward edge of the metallic strip and having a hump formed on the upper edge thereof provided with a V-shaped rear edge, the forward edge of the metallic strip being provided with a V-shaped notch to receive said V-shaped edge.

In testimony whereof I affix my signature.

FRANK P. McCORD.
